UNITED STATES PATENT OFFICE.

ADOLPH HARRY LICHTER, OF SPRINGFIELD, MASSACHUSETTS, ASSIGNOR TO STEVENS-DURYEA COMPANY, OF CHICOPEE FALLS, MASSACHUSETTS, A CORPORATION OF MASSACHUSETTS.

VEHICLE-TOP.

1,148,598.

Specification of Letters Patent.

Patented Aug. 3, 1915.

Application filed March 10, 1914. Serial No. 823,646.

To all whom it may concern:

Be it known that I, ADOLPH HARRY LICHTER, of Springfield, in the State of Massachusetts, have invented certain new and useful improvements in Vehicle-Tops, of which the following is a specification.

The side curtains for vehicles, such as automobiles, when not in use, may either be detached entirely from the top and stored under the seat or in some other separate receptacle, or they may be formed of light material and folded tightly together in a limited space and carried by the top itself.

This invention relates to improvements for carrying the folded type of curtain and relates particularly to means for securing and storing the curtain.

One of the objects of the invention is to provide a storage receptacle for the side curtains that will not use or limit any space desired for the occupants of the vehicle and that will be placed so that it will be entirely concealed from view, either from within or from without the vehicle.

A further object of the invention is to suspend the storage receptacle in the top between the outer portion or cover and the inner portion or lining without pressure or bearing upon the lining and in such manner that the top may be folded back in the usual way without removing the curtains.

Various other objects and advantages of the invention will be obvious, and still others will be more fully set forth in the following description of the particular embodiment of the invention shown in the accompanying drawings, in which—

Figure 1 is a side elevation, partly in section, of a vehicle top showing the curtain in its open position. Fig. 2 is a detail side view partly in section showing the curtain folded in place in the top. Fig. 3 is a side view, partly in section, showing the top folded with the curtain in place. Fig. 4 represents a cross-section of the top showing the curtain in place and means for securing same. Fig. 5 is a detail view of the curtain in its partly folded position. Fig. 6 is a detail view showing the curtain in its folded position.

As illustrated in the accompanying drawings, the top comprises a plurality of rigid bows 1 which support an outer cover 2 and an inner lining 3. The bows are spaced in their opened positions by flexible tension

straps or members 4 usually secured to the bows immediately below the cover. The cover and lining each have a central or horizontal portion and the depending approximately vertical side portions 2^a and 3^a respectively in the usual manner.

Arranged between the cover and lining at the front and back of the top are the storage receptacles 5 of suitable strong material. Each receptacle may contain two curtains or a separate receptacle may be provided for each curtain, as desired. Each receptacle is supported by means of straps or a continuous web of strong material 6 fixed to two of the bows so that the receptacle will be held out of contact with the inner lining. If desired, the receptacle may also be secured to the tension straps 4 which hold it open and may assist, to a limited extent, in supporting and steadyng the receptacle.

The curtain 8 is formed of flexible material and preferably is provided at spaced intervals with inserts of celluloid, mica or other material 9 that is somewhat flexible. The curtain is secured to the receptacle by means of a strap, cord or other flexible connection 10 attached near the corner of the curtain and fastened to the receptacle, as at 11, intermediate the ends thereof. The strap or other connection is of proper length to support the rear end of the curtain in position to be readily attached to the top and to the vehicle body for use and is also of the proper length to form a stop for the curtain when it is stored in the receptacle and thus determine its position therein. While in use, the curtain is secured to the body of the vehicle and to the lower edge of the lining in any suitable manner as the snaps or buttons 12. If desired, the lower ends of the receptacle may be provided with some suitable reinforcement 13, so as to hold the same in a slightly flaring position. After the curtain has been inserted, the opening is closed by any suitable means, as the flap 14.

The two parts of the curtain on each side of the vehicle may be secured together by any suitable means as the snaps or buttons 12^a forming a continuous side wall. When released from its fastenings, each portion of the curtain is folded upon itself in a compact mass comprising layers or leaves approximately perpendicular to the line of the curtain which is turned or twisted sidewise and then slipped endwise into the receptacle,

until further movement is stopped by the strap 10. This causes the curtain to lie in a substantially horizontal position, and keeps the curtain inserts of celluloid, mica or other material perfectly flat. The curtains on opposite sides are inserted from opposite ends of the receptacle so that the front half of each curtain is carried in the front receptacle and the rear half of each curtain is carried in the rear receptacle. When the curtain is in place the flaps 14 are buttoned or otherwise secured, which prevents the curtain from slipping out in case it is accidentally dislodged by movement of the vehicle. Owing to the fact that practically all of each curtain except perhaps the lower and flexible end thereof below the inserts is in a horizontal position, it is possible to fold the top in the usual manner without removing the curtains from their receptacles. By means of this construction, the curtains are entirely concealed in a space not otherwise available for use and do not limit in any way the capacity of the vehicle.

The supporting web which may be of specially prepared cloth or webbing is slightly wider than the distance between the adjacent bows so that it sags between the same forming a pocket above the lining and below the cover. The entire weight of the receptacle and inclosed curtains is transmitted directly to the tops of the bows where the web is preferably attached adjacent the cover and consequently, neither the cover or the lining is wrinkled or distorted in any manner. The flexible character of the web and the location of the receptacle in the sagging portion thereof intermediate the bows permits the top to be lowered without removing the curtain or without bending the celluloid, mica or other insert therein and the curtain always maintains a trim and neat appearance.

While I have shown and described, and have pointed out in the annexed claims, certain novel features of my invention, it will be understood that various omissions, substitutions and changes in the form and details of the device illustrated and in its operation may be made by those skilled in the art without departing from the spirit of the invention.

I claim—

1. In a device of the character described, the combination with a top comprising a cover and lining and a plurality of bows between said cover and lining, of a receptacle between the cover and the lining arranged parallel to the bows, a curtain adapted to be folded into said receptacle and means for supporting the receptacle and curtain comprising a flexible member extending between adjacent bows beneath the receptacle and above the lining.

2. In a device of the character described,

the combination of a top comprising a cover and lining and a plurality of bows between said cover and lining, tension straps between the bows, a supporting web swung from the tops of adjacent bows and sagging in the space between the bows above the lining, and a curtain receptacle mounted between said web and the tension straps and supported by said web out of contact with the lining.

3. In a device of the character described, the combination with a top comprising a cover and lining and a plurality of bows between said cover and lining, of a supporting member secured to the tops of the bows adjacent the cover and sagging between same toward the lining, and a curtain receptacle arranged parallel to the bows and supported by the web below the cover and above the lining.

4. In a device of the character described, the combination with a top comprising a cover and lining and a plurality of bows between said cover and lining for said bows, of a receptacle between the lining and the cover and supporting means for said receptacle secured to the bows and holding the receptacle out of contact with the lining.

5. In a device of the character described, the combination with a vehicle top comprising a plurality of bows, a cover and a lining for said bows, and a receptacle supported between the cover and lining and concealed thereby, of a curtain adapted to be folded, and flexible holding means for the curtain permitting the same to be turned after being folded and to be slipped endwise into the receptacle.

6. A vehicle top comprising a plurality of rigid bows, a cover and lining for said bows, a receptacle supported from the bows between the cover and lining, a curtain adapted to be folded into said receptacle, and means to support a portion of the curtain in position for ready attachment to the vehicle, said means being folded into the receptacle with the curtain.

7. The combination with a vehicle top comprising a plurality of rigid bows and a cover and lining for said bows, of a storage receptacle supported directly by the bows between the cover and lining, a curtain adapted to be folded into said receptacle, and means for permanently securing the curtain to the receptacle, said securing means being attached to the receptacle intermediate its ends and being adapted to be folded in the receptacle with the curtain.

8. The combination with a vehicle top comprising rigid bows and a flexible cover and lining therefor, of a storage receptacle supported directly by said bows between the cover and the lining and extending across said top, a curtain adapted to be folded into the receptacle, means for limiting

movement of the curtain within the receptacle and means for securing said curtain within the receptacle in its closed position.

9. The combination with a vehicle top comprising rigid bows and a cover and a lining therefor, of a receptacle parallel to the bows and having an approximately horizontal central portion and an approximately vertical end portion, said receptacle being entirely concealed between the cover and the lining, means for supporting said receptacle directly from the bows, a curtain adapted to be folded and passed through

the vertical portion of the receptacle into the horizontal portion thereof, and means 15 for securing the curtain to the receptacle adapted to be automatically folded within the receptacle when the curtain is inserted therein.

This specification signed and witnessed 20 this 26th day of February, A. D., 1914.

ADOLPH HARRY LICHTER.
